CLOCK ATTACHMENT FOR FLAT KNITTING MACHINES

Woldemar Heinitz, Chemnitz, Germany, assignor to Schubert & Salzer Maschinenfabrik Aktiengesellschaft, Chemnitz, Germany

Application November 21, 1935, Serial No. 50,944
In Germany December 6, 1934

2 Claims. (Cl. 66—96)

The present invention relates to flat knitting machines for producing stockings in a single operation and is, more particularly, concerned with a clock attachment adapted to be used in connection with such knitting machines for the manufacture of forked clock designs in stockings.

On flat knitting machines for the manufacture of stockings in a single operation in which the loops on the needles producing the middle portion of the stocking are placed in suspense during the manufacture of the heel parts it has hitherto not been possible to produce in a simple manner a so-called clock fork, i. e. a forked clock design, one arm of which extends into the heel part, while the other arm extends into the middle portion of the stocking.

In the normal position the clock fingers occupy until the manufacture of the heel parts is started, 20 knitting of the heel parts would result in one of the clock fingers being moved into the free space between the heel parts. Therefore, means, allowing an alteration of the distance between the clock fingers, must be provided to prevent, on the one hand, movement of one of the clock fingers into the free space between the heel parts and, on the other hand, to simultaneously allow the production of the forked arms of the clock design in both heel parts. After finishing the heel parts 25 and at the beginning of the manufacture of the middle portion of the stocking it is, moreover, desirable to alter the distance between the two clock fingers in a manner allowing simultaneous manufacture of the arms of the forked clock design extending into the middle portion of the stocking.

A generally used method to obtain this purpose is to fix the two clock fingers upon two separately journaled clock finger bars and to displace the 40 two bars with respect to each other, until the desired distance between the two clock fingers is obtained.

This method of clock finger rack, however, offers difficulties when used in connection with 45 knitting machines adapted to produce stockings in a single operation, as the clock finger bars are used for other purposes, for instance by edge and picot members, and the like.

Under certain circumstances the addition of a 50 further clock finger bar would be possible, but as this bar must be mounted above the other bars, this arrangement would, on account of the required great length of the clock finger arm, deprive the clock point much of its rigidity.

55 According to the present invention, the alter-

ation of the distance between the clock fingers for the production of forked clock designs is obtained by the use of a divided clock finger bar. The clock finger bar according to the present invention consists of two commonly journaled 5 parts, forming a unit, which parts may be longitudinally moved with regard to each other.

The accompanying drawing shows the invention by way of example.

In this drawing: 10
Fig. 1 diagrammatically shows a side elevation of a portion of a stocking having a forked clock design;

Fig. 2 shows an elevation of the clock attachment according to the invention; 15

Fig. 3 is a section on line 3—3 of Fig. 2;

Fig. 4 is a detail elevation, showing the clock fingers in another position, and

Fig. 5 diagrammatically shows a piece of fabric, representing the arms of the forked clock 20 design obtained by the position of the clock fingers according to Figs. 2 and 4.

The clock finger bar used hitherto consists, according to the invention, of two parts 1 and 2 for instance of semi-circular cross section. The 25 two parts are journaled in a suitable manner in the frame of the machine, not shown in the drawing, and may be longitudinally shifted with respect to each other.

Upon the part 1 of the clock finger bar a sleeve 30 4 is fixed by means of screws 3 and provided on this sleeve is an arm 6 carrying the clock finger 5. The part 2 of the clock finger bar is shiftably arranged in the sleeve 4. Upon the part 2 of the clock finger bar a sleeve 8 is fixed by means 35 of screws 7 and provided on this sleeve is an arm 10 carrying the other clock finger 9. In the sleeve 8 the part 1 of the clock finger bar is shiftably arranged.

The two parts 1 and 2 of the clock finger bar 40 may be connected together by a clutch to prevent mutual displacement during operation. As shown more particularly in Fig. 3, the clutch substantially consists of a slotted ring 11 the opposed ends of which are provided with bosses 45 12, 13. Both bosses 12, 13 have a bore and the bore of the boss 13 is provided with a thread for cooperation with a screw 14 freely passing through the bore of the boss 12. The upper end of the screw 14 carries a handle 15 for facilitating clamping and releasing of the clutch ring 11. An L-shaped guide member 16 consists of one piece with or is connected to the clutch ring 11 and in this guide member 16 a slide 17, 18 is adjustably mounted. The lower end 18 of the 50 55

slide 17, 18 has about the shape of a trapezoid and in this portion of the slide two slots 19 and 20 are provided which are arranged at about 45° towards the longitudinal axis of the two parts 1 and 2 of the clock finger bar. Slidably fitted in the inclined slot 19 is a pin 21 fixed to the part 1 of the clock finger bar, and in the inclined slot 20 a pin 22 fixed to the part 2 of the clock finger bar slidably engages. The part 17 of the slide 17, 18 is provided at about its middle portion with three notches 23 in which a screw 24 inserted into the guide member 16 may engage for the purpose of holding the slide 17, 18 in its different positions of adjustment in which the distance of the clock fingers 5 and 9 from each other is, for a purpose stated presently, equal to the distance I, II and III respectively.

The operation of the clock attachment according to the present invention for the production of forked clock designs in stockings made in a single operation on a flat knitting machine is as follows:

If during the manufacture of the leg portion A of a stocking (Fig. 5), clock designs are to be produced at the places marked $a-b$ and $a'-b'$ and further at the places marked $b-c$ and $b-d$ and $b'-c'$ and $b'-d'$ respectively, the clock fingers 5 and 9 first must be adjusted to be separated from each other by the distance I. For effecting this adjustment the clutch ring 11 is released by loosening the screw 14, 15 to allow mutual displacement of the parts 1, 2 of the clock finger bar. Thereupon the screw 24 is loosened and the slide 17, 18 moved downwardly from its highest position shown in Fig. 2 until the screw 24 may engage into the middle notch 23 of the slide member 17. During the downward movement of the slide 17, 18 the pins 21 and 22 respectively slide in the corresponding inclined slots 19 and 20, whereby the parts 1 and 2 of the clock finger bar are displaced with respect to each other until the distance between the clock fingers 5 and 9 is equal to the distance I, so that after clamping of the clutch 11 by means of the screw 14, 15 the clock fingers 5 and 9 may work the clock design in the above mentioned portions of the stocking.

As soon as the manufacture of the heel parts is started at which time the needles carrying the loops of the middle portion of the stocking are placed in suspense, one of the clock fingers would, if the distance between them would remain equal to the distance I, operate in the heel part, whereas the clock finger at the other side would simultaneously be positioned in the space of the middle portion of the stocking placed in suspense.

Such operation, of course, is not desirable and therefore, before starting with the manufacture of the heel parts, it is necessary to alter the distance of the clock fingers from each other in such a manner, that the clock fingers 5 and 9 may operate in the corresponding heel parts.

For this purpose the clutch ring 11 is again released by turning the screw 14, 15, whereupon, after loosening of the screw 24, the slide 17, 18

is moved into its uppermost position, shown in Fig. 2, in which the screw 24 may engage the lowermost notch 23 in the slide 17, 18. The clock fingers 5 and 9 are now positioned in the distance II from each other, so that, after clamping the clutch ring 11 by tightening the screw 14, 15, the clock design may be produced in both heel parts simultaneously at $c-e$ and $c'-e'$ respectively.

After finishing the heel parts, an alteration of the distance of the clock fingers 5 and 9 from each other is again required, to allow the manufacture of the clock design at $d-f$ and $d'-f'$ respectively in the middle portion of the stocking which now is about to be knitted. Therefore, the clutch ring 11 is again released by turning the screw 14, 15 and, after loosening of the screw 24, the slide 17, 18 is brought in its lowermost position in which the pins 21, 22 lie at the upper ends of the inclined slots 19 and 20 respectively, i. e. the clock fingers 5 and 9 are shifted with regard to each other, until they occupy the position shown in Fig. 4 in which the distance from each other is equal to the distance III. The screw 14, 15 is tightened again, to fix the clutch ring 11 and thereby the clock fingers 5 and 9 in the desired position with regard to each other, so that the clock designs may be produced at $d-f$ and $d'-f'$ respectively as shown in Fig. 5.

It is to be understood, that the present invention is not limited to the construction shown and described, as modifications may be made without departing from the spirit of the invention.

What I claim is:

1. A clock attachment for flat knitting machines, comprising a clock finger support, consisting of two bars, a sleeve fixed to each of said bars and forming a guide for the other of said bars, a clock finger at each of said sleeves, a clutch, consisting of an open ring, surrounding said bars, a screw passing through bosses near the ends of said open ring and adapted to firmly clamp said ring on said bars, a guide member on said ring, a slide, having slots inclined in opposite directions towards said clock finger support, adapted to be guided in said guide member, a screw inserted in said guide member and adapted to engage notches provided in said slide, and a pin, connected to each of said bars forming said clock finger support, each of said pins engaging one of said inclined slots in said slide.

2. A clock attachment adapted to produce forked clock designs in stockings made in a single operation on flat knitting machines on which the middle portion of the fabric is placed in suspense during the manufacture of the heel parts, comprising a clock finger support consisting of two bars, means carried by said bars for coupling said bars for unison of movement during operation, means connected to said coupling means for shifting said bars with respect to each other, and means for positively fixing said bars in each adjusted operative position.
